(57) **CLAIM**

The ornamental design for a wireless earbud as shown and described.

DESCRIPTION

Fig. 1.1 is a front elevation view of the wireless earbud according to our design;

Fig. 1.2 is a rear elevation view thereof;

Fig. 1.3 is a left elevation view thereof;

Fig. 1.4 is a right elevation view thereof;

Fig. 1.5 is a top thereof;

Fig. 1.6 is a bottom view thereof;

(Continued)

Fig. 1.7 is front-right-bottom perspective view thereof;
Fig. 1.8 is a rear-left-top elevation view thereof.

1 Claim, 8 Drawing Sheets
